UNITED STATES PATENT OFFICE.

ROBERT B. BEST, OF GREAT NECK, NEW YORK.

ASBESTOS HANDLE.

1,079,688.

Specification of Letters Patent. Patented Nov. 25, 1913.

Application filed May 13, 1913. Serial No. 767,483.

To all whom it may concern:

Be it known that I, ROBERT B. BEST, a citizen of the United States, residing at Great Neck, Long Island, in the county of 5 Nassau and State of New York, have invented a new and useful Asbestos Handle, of which the following is a specification.

This invention relates to improvements in asbestos handles whereby a handle is provided which is adapted to resist the destructive action of heat and to remain in a cool condition.

A further object is to provide a handle with an air chamber extending longitudinally of the same whereby a circulation of air will be provided to keep the handle in a cooled condition.

A further object is to provide a handle comprising a hollow metallic core with an 10 outstanding flange at one end thereof and to which is rigidly secured the body portion of compressed asbestos or other heat resisting substance having a high thermal resistance.

With the foregoing and other objects in view which will appear as the description proceeds, the invention resides in the combination and arrangement of parts and in the details of construction hereinafter described and claimed, it being understood that 20 changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

Figure 1 is a view in elevation illustrating my improved form of asbestos handle. Fig. 40 2 is a longitudinal sectional view thereof.

Referring to the drawings in which similar reference numerals designate corresponding parts throughout the several views, 1 is the handle core which is hollow cylindrical 45 in form and provided with the enlarged head 2 internally threaded as at 3 so that the handle may be detachably secured to soldering irons, pokers, branding irons or other similar tools which of necessity are placed 50 in fires and require a handle formed of some heat resisting material. The enlarged internally threaded end 3 is provided with the outstanding annular flange 4 illustrated as being integral therewith and which provides 55 a suitable stop or shoulder against which the compressed asbestos body portion 5 contacts

with. The opposite end of the hollow core 1 is externally threaded as at 6 and engaging the same is the securing nut 7. The body portion 5 preferably formed of compressed asbestos is provided with a suitable axial opening 8 extending therethrough and which is adapted to fit over and conform to the outer peripheral surface of the core 1. The securing nut 7 is embedded in the body portion so as to be flush therewith and to eliminate all sharp projections.

In order to insure that the entire handle will be maintained in as cool a condition as possible, suitable apertures 9 are provided 70 in the enlarged end of the core beyond the flange 4 and these apertures in connection with the open end 10 of the core provide for the circulation of air through the core to thereby maintain the same and the entire 75 handle in a cool condition.

It has been found in practice that asbestos possesses a high coefficient of thermal resistance and therefore heat from the core will not pass through the body portion 5 to any 80 great extent. Furthermore inasmuch as a constant circulation of air has been provided for, the core will not be heated to any excessive temperature under all ordinary conditions. Furthermore asbestos has been found 85 to successfully withstand the direct contact with flames so that accidents which would destroy ordinary handles would have little effect upon the one herein described. Furthermore due to the high coefficient of thermal resistance, which is the same as saying that the material has a low coefficient of 90 thermal conductivity, the device provides that, though the asbestos itself be at a high temperature, the effect upon the hand of the 95 operator will not be largely influenced thereby, as it would if the substance forming the body portion of the handle was of some material having a high coefficient of conductivity. Furthermore, mention is made of the 100 fact that the body portion of compressed asbestos is removably secured to the hollow core and may be replaced after the useful life thereof has expired.

What I claim is:—

In a device of the class described the combination of a hollow core, means located at one end thereof whereby the same may be affixed to an article to act as a handle therefor, an outstanding flange carried by said core 110 adjacent the said end, a fire resisting body portion having a low coefficient of thermal

conductivity detachably secured to said core, having surface contact therewith, abutting said flange, and of a relatively smaller diameter than the said flange at its point of contact therewith, means engaging the opposite external end of said core, contacting with the said body portion and adapted to hold the same rigidly in place, said core provided with a plurality of air ducts extending through the side wall thereof intermediate its end and said flange, the opposite end of

said core open to the atmosphere for the free circulation of air therethrough for the cooling thereof.

In testimony that I claim the foregoing as 15 my own, I have hereto affixed my signature in the presence of two witnesses.

ROBERT B. BEST.
